UNITED STATES PATENT OFFICE.

JOSEPH E. GADBOIS, OF SPRINGFIELD, MASSACHUSETTS.

MAGAZINE-GUN.

1,193,889.

Specification of Letters Patent.

Patented Aug. 8, 1916.

Application filed December 8, 1915. Serial No. 65,841.

To all whom it may concern:

Be it known that I, JOSEPH E. GADBOIS, a citizen of the United States, residing at Springfield, in the county of Hampden and 5 State of Massachusetts, have invented a new and useful Improvement in Magazine-Guns, of which the following is a specification.

This invention has particular reference 10 to that type in which the cartridges are automatically fed, the only manual operation being that of pulling the trigger.

The primary aim is to provide such a gun which will operate efficiently throughout 15 and be capable of carrying a large supply of ammunition.

The invention further resides in the construction and combination of parts herein-after described and claimed the preferred 20 embodiment being illustrated in the drawings, wherein,

Figure 1 is a vertical longitudinal section of a gun stock or butt showing the invention, in part, therein. Fig. 2 is a horizontal section taken longitudinally of the 25 stock. Fig. 3 is a partial side elevation of the mechanism for pushing the cartridges from the carriers to the magazine chamber. Fig. 4 is a rear elevation thereof. Fig. 5 shows in top plan, partly broken away, the 30 cartridge pushing mechanism in position for advancing the cartridge carriers. Fig. 6 is a similar view with the mechanism pushing the cartridges from the carriers.

Figs. 7, 8, 9, 10, 11 and 12 are detailed elevations of the mechanism parts. Fig. 13 is 35 a horizontal section through the firing drum, the cartridge feeding and ejecting mechanism therefor and the drum rotating means.

Fig. 14 is a side elevation of the drum rotating means. Fig. 15 shows the drum in rear elevation. Fig. 16 depicts the same in partial side elevation. Fig. 17 is 40 a view of the opposite side of the drum rotating means. Fig. 18 shows the drum locking means inoperative. Fig. 19 is a similar section with the means operative.

Fig. 20 is a longitudinal section through the cartridge magazine. Fig. 21 is a transverse 45 section through the cartridge carriers illustrating the manner of supporting the same. Fig. 22 shows three of the carriers in end elevation with a fragment of their endless support. Fig. 23 is a perspective of one of 50 the carriers. Fig. 24 shows the hammer with its tripping star wheel, and Figs. 25

and 26 illustrate in section the mounting of the star wheel on the trigger, the latter being in fragment.

The numeral 1 designates the barrel and 60 2 the hollow stock of the gun, a firing drum 3 being rotatably journaled in the stock to present its cartridge chambers 4 at the rear end of the barrel and in coincidence with the bore thereof. The hammer 5 for firing 65 the cartridges, as presented in alinement with the barrel, is pivoted at 6 in the stock and held slightly spaced from the drum, to permit of rotation of the latter, by the leaf spring 7 which actuates and returns the 70 hammer to normal position.

The hammer is tripped by a star wheel 8 journaled on the pivot 9 of the trigger 10, the latter carrying a yieldable dog 11 to engage with a ratchet 12 fixed to the star 75 wheel whereby on pulling the trigger, the wheel will partly rotate to trip the hammer, and on releasing the trigger, to return under the action of its spring 13, the dog 11 will ride over the ratchet without affecting 80 the hammer.

The firing drum is provided with a tubular shaft extension 14 carrying a fixed ratchet 15 with which a pawl 16 engages for retaining the drum from reverse movement. 85 Proper rotation is effected by a dog 17 yieldably mounted on an oscillatory disk 18 which has a slotted radial arm 19. The trigger is provided with an arm 20 engaging in the slot of arm 19 and adapted, when 90 the trigger is pulled, to swing said slotted arm and the dog 17, the latter, being engaged with the ratchet 15, moving the same therewith and consequently turning the drum. 95

In the present instance, the firing drum is only provided with four cartridge chambers so that each movement of the drum will be a quarter turn, it being obvious that a greater or lesser number of such chambers may be provided.

The dog 17 rides reversely over the ratchet 15, and, while the latter is held from backward movement by the pawl 16, the co-operating arms 19 and 20 retain the drum 105 from forward movement until the trigger is pulled.

The cartridge magazine 21 is provided with a lower chamber 22 into which the cartridges drop singly and which is alined with 110 the next succeeding cartridge chamber 4. A charging plunger 23 slides in the lower

- chamber 22 for loading the drum chamber. The plunger is of sufficient length to close the opening in the magazine leading to the lower chamber to support the next cartridge 5 from falling until the plunger has returned to inoperative position. The cartridges in the magazine are advanced simultaneously with the loading of a drum chamber by a follower 24 which is connected to the plunger by a stem 25 having a rack part 26. A pinion 27 is interposed in intermeshing relation between the rack 26 and an opposing, slidable rack 28 which is connected to the trigger by a link 29.
- 10 It will thus be noted that as the trigger is pulled the plunger is retracted to allow another cartridge to drop into the lower chamber 22, and when released, the plunger is advanced to load the drum chamber.
- 15 An ejector 30 is slidable in the central bore 31 of the firing drum and has its forward terminal bent backwardly and headed, as at 32, to enter the forward ends of the cartridge chambers 4 and eject the used shell 20 (see Fig. 13). The ejector is normally maintained free of the drum or in a forward position, by a spring 33 and has its rear end formed into a hook 34 with which a spring catch 35, carried by the slidable rack 28, is 25 adapted to engage when the trigger is pulled so that the ejector will be moved rearwardly into a drum chamber for cleaning the latter when the trigger is released. Thus, after a cartridge chamber has been loaded, the 30 next two movements of the drum will present the said chamber at firing and ejecting 35 positions, respectively.

During the firing of the cartridge, the drum is locked by a slidably mounted bolt 40 36 engaging in the respective keeper recess 37, of a series provided in the firing drum. The bolt is spring projected and is normally withdrawn from engagement with the drum by having its angular rear end 36' coöperative with a cam 38 on the disk 18 to permit 45 of rotation of said drum.

The magazine is supplied with cartridges by an endless series of carriers 39 supported on a chain 40 which takes over longitudinally spaced sprockets 41 and 42 journaled in the gun stock. The forward sprocket 41 is fixed on a transverse shaft 43 having a longitudinal groove 44 in which a key 45 of wheel 46 slidably engages. This wheel has 50 55 radial, hook-shaped arms 47 with which the downturned end of arm 48 is adapted to engage, said arm 48 extending laterally from the stem 25. Obviously, forward movement of the plunger 23 will effect partial rotation 60 of the sprocket 41, when the wheel 46 is in the path of the arm 48, and advance the carriers 39.

Each carrier is of box form having side walls and an interposed end wall provided 65 with an opening 49 therein through which a

pusher 50 is adapted to move for forcing the cartridges from the opposite end of the carrier into the magazine. The pusher is arranged directly opposite the inlet opening of the magazine, the carriers moving therebetween. Each rotary movement of the wheel 46 presents a loaded carrier between the pusher and the magazine opening.

The pusher is of angular formation having a horizontal base 50' adapted to move 75 beneath the carriers, said base having a downturned follower extension 51 projecting through a guide slot formed in the track or bridge 52. The follower 51 operates in the cam slot 53 of a revoluble barrel 54, said 80 cam slot comprising a spiral section and a straight or longitudinal section joining the ends of the spiral. A ratchet 55 is fixed to the barrel 54 and is held against backward movement by a pawl 56 while forward motion is imparted by the rod 57 connected to the trigger and engaging the ratchet. As the barrel 54 is revolved, by pulling the trigger, the follower and pusher are advanced 85 so that a cartridge is fed to the magazine 90 every time one is fired.

While the pusher is in a carrier, it is essential that the latter be not advanced and to this end, the wheel 46 is peripherally grooved at 95 58 to receive a yoke 59 which extends forwardly from the follower 51 whereby the wheel is shifted from the path of arm 48 when the pusher begins its transverse movement. Rotation of the barrel 54 causes the follower to travel in the spiral section and, 100 when the last cartridge of the carrier is moved into the magazine, the follower enters the straight groove section and is pulled back or retracted to normal position, in which the pusher is free of the carrier, by coiled spring 105 60. This action brings the wheel 46 into the path of arm 48 for advancing a fresh carrier.

Briefly the operation is as follows: The initial pull on the trigger will rotate the 110 firing drum to bring a cartridge chamber from the magazine to the hammer and there be locked by bolt 36. Continued pulling on the trigger actuates the hammer, advances catch 35 into engagement with the ejector, 115 retracts the plunger 23 to permit of another cartridge dropping into the lower chamber, slides the follower 24 in the magazine backwardly to allow a cartridge from the carriers being inserted, and revolving the barrel 54 to actuate the pusher. When the trigger is released, the bolt 36 is disengaged from the drum, the ejector actuated, and the plunger 23 and follower 24 moved to advance the cartridges in their paths. A lug 120 61 disposed in the path of the catch 35 engages the latter when actuating the ejector and provides a cam action to disengage the catch. If the last cartridge has been removed from a carrier, the arm 48 engages 125 65

wheel 46, when the trigger is released, for advancing the carriers.

Having thus described my invention, what I claim as new and desire to secure by Letters Patent is—

1. In a magazine gun, an endless series of cartridge carriers, a magazine, means for moving cartridges from the carriers to the magazine, a firing drum, means for feeding 10 the cartridges to the latter from the magazine, a hammer for firing the cartridges in the drum, an ejector, and a trigger controlling the aforesaid means, hammer and ejector.
- 15 2. In a magazine gun, a firing drum, a magazine having a lower chamber from which cartridges are loaded into the drum, said chamber communicating with the magazine, a plunger in said chamber for 20 moving the cartridges into the firing drum and closing communication between the chamber and magazine, a follower in the latter connected for movement with the plunger, and a firing mechanism operative 25 to actuate the plunger.
3. In a magazine gun, a rotatable firing drum having cartridge chambers and an axial opening, an ejector slideable in the drum opening and adapted for entering the 30 chambers, a hammer, a trigger, and a releasable connection between the trigger and ejector.
4. In a magazine gun, a rotary firing drum, means for feeding cartridges thereto, 35 a hammer, means for rotating the drum, and a trigger for operating the hammer and the aforesaid means.
5. In a magazine gun, a hollow stock, spaced sprockets therein, a chain taking over 40 the sprockets, a series of carriers on the
- chain, a magazine having a receiving opening opposite which the carriers are adapted to move, means for intermittently driving the sprockets, and a firing mechanism into which the magazine leads. 45
6. In a magazine gun, a hollow stock, a series of carriers, a magazine having a receiving opening into which the cartridges are fed from the carriers, a firing mechanism to which the magazine leads, and means for 50 moving the carriers intermittently to present them individually at the receiving opening of the magazine.
7. In a magazine gun, a cartridge feeding mechanism including a series of carriers, a 55 pusher normally free of the carriers and movable transversely thereof to feed the cartridges therefrom, means for moving the pusher intermittently, and means under control of the pusher for moving the carriers. 60
8. In a magazine gun, a cartridge chamber, an ejector therefor, a firing mechanism including a trigger, and means operable by the trigger to releasably engage the ejector to actuate the latter. 65
9. In a magazine gun, a rotatable drum, means for rotating the same, a magazine, plunger means therein, a series of carriers, means for moving the carriers, a pusher for moving the cartridges from the carriers to 70 the magazine, means for operating the pusher, a hammer, and a trigger for actuating the hammer and aforesaid means.

In testimony whereof I have signed my name to this specification in the presence of 75 two subscribing witnesses.

JOSEPH E. GADBOIS.
